Inventor:

Robert John

By Frank L. Belknap, Jr.

UNITED STATES PATENT OFFICE

ROBERT JOHN, OF LONG BRANCH, NEW JERSEY, ASSIGNOR TO AQUATONE CORPORATION, OF CHICAGO, ILLINOIS, A CORPORATION OF DELAWARE

DEVICE FOR WASHING OR TREATING PLATES

Application filed May 19, 1930. Serial No. 453,589.

This invention relates to improvements in devices for washing or treating plates, and is here shown embodied in a device especially adapted for use with large photographic plates, as for example, photolithographic plates. In the art of photography, it frequently is necessary to wash or treat a large plate with a solution. For example, in the art of photography the surface of a plate may have to be washed with water or treated with some other liquid, for example, a mixture of formaldehyde and alcohol to harden and dry the film on the plate.

Among the features of my invention, is the provision of a device that will keep the plate at all times covered with the liquid being used, keep the liquid in circulation on the plate, and also maintain a uniform temperature of the plate and liquid.

Other features and advantages of my invention will appear more fully as I proceed with my specification.

In that form of device embodying the features of my invention shown in the accompanying drawing, Fig. 1 is a vertical sectional view, and Fig. 2 is a view taken as indicated by the line 2—2 of Fig. 1.

As shown in the drawing, 10 indicates a flat box-like plate support preferably having a metal lining, and provided with a false bottom 11 to provide a chamber 12 for the circulation of a refrigerating or heating medium. The space 12 is preferably provided with the baffles 13 so that a refrigerating medium, as for example, water will be caused to circulate therethrough as indicated by the arrows in Fig. 2. 14 indicates an inlet pipe for the refrigerating medium and 15 a suitable outlet pipe.

16 indicates a plate being treated which is adapted to rest on the false bottom 11 and be held in place by suitable studs or posts 17.

18 indicates a suitable standard for the centrally arranged stationary post 19 on the upper end of which the tray or plate holder 10 is supported by means of the universal joint 20.

Rotatably mounted in the standard 18 is a sleeve 21 surrounding the post 20 and provided on its upper end with a circular plate

22. The sleeve is rotatably mounted in the standard by means of the thrust bearing 23 at the lower end and the centering bearing 24 at the upper end. Any suitable means may be provided for rotating the sleeve 21 and disc 22. For this purpose, I have here shown a worm gear 25 fixed on the sleeve 21 and adapted to be driven by the worm 26 on the shaft 27 which in turn may be driven by any suitable source of power, as for example, the motor 28.

The disc 22 carries auxiliary supports here shown as the beveled rollers 29, 29a substantially equally spaced about its periphery. Two of these rollers 29, 29a adjacent to each other are mounted on the posts 30 to elevate the same some distance above the lower two rollers 29, 29a. The rollers 29, 29a are adapted to ride on a circular track 31 on the underside of the tray 10. The parts are so arranged that although a substantial part of the weight of the tray is taken by the bearing 20, the rollers 29, 29a will all be substantially in contact with the track 31 thus causing the tray to assume a slanting position as shown in Fig. 1.

32 indicates a suitable post or anchorage carrying one end of a chain 33 having its other end attached to a part of the tray 10 to limit rotation of the tray. The anchorage is effected through a flexible member such as a chain 33 so that during the operation of the device the tray 10 will be given a reciprocating rotary motion.

In the operation of the device, the wheel 28 is rotated to rotate the sleeve 21, and disc 22 thus causing the rollers 29, 29a to travel around the track 31. The rotation of these rollers obviously causes a rotary shifting of the direction of slant of the tray. The flexible anchorage 33 limits rotation of the tray but permits it to have an uneven or non-uniform rotary motion, as the result of imposing the reciprocating motion on the rotary motion. This is accomplished as follows: When the anchorage point as indicated by 34 is the lowest point, the chain 33 will lie in a vertical plane passing substantially through the center of the device. In other words, the point 34 will be as nearly under the top of

the post 32 as possible. As the table 22 rotates to change the direction of slant of the tray, the point 34 will rise and the chain 33 will then permit the tray to rotate with the rollers 29, 29a a certain distance. That is, as the point 34 rides, the chain 33 will permit it to lead or rotate forwardly to hold the chain taut. As the point 34 again lowers and the chain 33 becomes more nearly vertical, the point 34 will be brought back again to a position substantially under the top of the post 32. It will be seen, therefore, that the rollers 29, 29a tend to rotate the tray 10. Such rotation is limited by the chain 33 but because of the raising and lowering of the point of attachment 34, such chain permits a certain amount of reciprocating rotary motion of the tray.

35 indicates a suitable drain pipe for the tray 10.

In the use of the device, a sufficient amount of solution is put in the tray to keep the plate substantially covered. The wobbling motion given to the tray as above described keeps the plate covered with a relatively small amount of solution besides keeping the same in circulation. I have found that if the disc 22 is driven at the rate of 22 rotations per minute, satisfactory results may be obtained.

30 While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty in my invention as broadly as possible in view of the prior art.

40 I claim as my invention:

1. In a device of the character described, a suitable support, a slanting tray mounted on the support by a universal joint, means for rotatively changing the direction of slant of the tray, said means comprising a plurality of supports rotatably mounted below the tray around the universal joint, one of said supports being higher than the other, whereby upon rotation of said supports the direction of slant of the tray is rotatively changed, and a flexible anchorage for the tray, said flexible anchorage limiting rotation thereof, but permitting reciprocatory rotary movement of the tray.

55 2. In a device of the character described, a slanting tray having a false bottom to provide a chamber beneath, means for circulating a fluid in the chamber below the false bottom, means for rotatively changing the direction of the slant of the tray, and means for simultaneously imparting a substantially horizontal oscillatory movement to the tray while preventing lateral movement of said tray.

65 3. In a device of the character described,

a suitable main support, a slanting tray mounted on the top of said main support by a universal joint, a plurality of auxiliary supports rotatably mounted on the main support around the universal joint, one of said supports being higher than the others, whereby upon rotation of said auxiliary supports the direction of slant of the tray is rotatively changed, and a flexible anchorage for the tray to limit rotation thereof but 70 permit the change of direction of slant and also permit reciprocatory rotary movement of the tray.

In testimony whereof I affix my signature.

ROBERT JOHN.
